Patented Jan. 4, 1921.

UNITED STATES PATENT OFFICE.

WILLIAM CLINTON BROWN, OF SYRACUSE, NEW YORK, ASSIGNOR TO STUMPF UNA-FLOW ENGINE COMPANY, A CORPORATION OF NEW YORK.

AUXILIARY CLEARANCE.

1,364,070.

Specification of Letters Patent. Patented Jan. 4, 1921.

Application filed May 24, 1918. Serial No. 236,268.

To all whom it may concern:

Be it known that I, WILLIAM CLINTON BROWN, a citizen of the United States, residing at Syracuse in the county of Onondaga, State of New York, have invented new and useful Improvements in Auxiliary Clearance, of which the following is a specification.

The invention relates to improvements in auxiliary clearance. The object is to provide automatic means for relieving excessive pressures in the cylinder and arbitrarily operated means for establishing communication between the cylinder and a closed or limited auxiliary clearance space.

A una-flow engine when operating condensing requires a smaller clearance than when running non-condensing, so that if an engine is to be constructed to operate both condensing and non-condensing it is customary to provide an auxiliary clearance pocket with a valve in the passage from the cylinder to this pocket, which is closed when the engine is running condensing and open when running non-condensing.

In case the vacuum suddenly breaks when the engine is running condensing, it is desirable that this valve shall open in order to prevent too great a pressure inside the cylinder. If this valve is made in the form of a safety valve opening into the pocket it will relieve the pressure at the end of the first stroke, but if the engine continues running the valve, acting like a check valve, will gradually build up the pressure in the pocket so that finally it will give no relief and there will be the dangerous compression in the cylinder.

The drawing is a horizontal section of the end of a cylinder showing the clearance space and a suitable embodiment of my valve control therefor.

The end of the power cylinder 1 is provided with a port 2 adapted to communicate with the auxiliary clearance space 3. This port 2 is provided with a valve seat 4 adapted to be controlled by a valve 5 normally held against the seat 4 by the action of the spring 6. The tension of the spring 5 is adjustable by means of the set-screw 7. A passage or port 8 is provided, leading from the clearance space 3 to any suitable exit such as drain 9. This passage or port 8 is provided with a valve seat 10 adapted 55 to be controlled by the upper side of the

valve 5. The valve 5 is adapted to be manually operated by means of the hand operated member 11 threaded into the housing 12.

In operation:—

It will be noted that the passage or port 2 is normally maintained closed by the valve 5, held in such closed position by the pressure of spring 6, so that in case the pressure rises above the safe point in the cylinder, this valve will open and permit the steam to pass into the auxiliary clearance space 3, and from the auxiliary clearance space 3 out through port 8 to drain 9, so that it is impossible to build up the pressure by continuous operation.

If this drain remain open and the valve 5 were opened by turning back the hand member 10, in order to permit the engine to run non-condensing there would be a leak right out through the cylinder which would not permit of a continuous operation, so that valve 5 is arranged to close off the port 8 to the drain, when it is operated by hand, by backing it up against the upper seat 10. It will thus be seen that when the valve is moved down against the bottom seat it shuts off the auxiliary clearance from the cylinder and opens the auxiliary clearance to the drain. When moved back against the upper seat it opens the auxiliary clearance to the cylinder and shuts off the auxiliary clearance from the drain. When moved down against the lower seat it acts as a safety valve to prevent any undue rise of pressure in the cylinder in case of loss of vacuum. There are very few cases if any, where it is desirable to change an engine from condensing to non-condensing automatically, excepting due to an accident to the condenser, and in that case it is not asking too much of the attendant to go to his engine and back off this valve. In the mean time the safety device prevents an excess of pressure in the cylinder.

What I claim is:—

1. The combination with a steam cylinder of means forming an auxiliary clearance chamber with a port provided with a valve seat located between the cylinder and the clearance chamber and a relief port provided with a valve seat in said clearance chamber, a valve adapted to coöperate with either valve seat, resilient means operating on said valve for normally maintaining the

port between the cylinder and the clearance chamber closed, responsive to excessive pressures in the cylinder acting directly on the valve to open said port during the period 5 only of said excessive pressure, and means for moving the valve from one valve seat to the other comprising a hand operated member relatively movable with respect to the valve seats, and a valve spindle having 10 a limited spring controlled movable relation with respect to the hand operated means.

2. The combination with a steam cylinder, of means forming an auxiliary clearance chamber with a port provided with a valve seat between the cylinder and said clearance chamber and a relief port provided with a valve seat in said clearance chamber, a valve 15 adapted to coöperate with either valve seat,

resilient means operating on said valve for normally maintaining the port between the cylinder and said clearance chamber closed, responsive to excessive pressures in the cylinder acting directly on the valve to open said port during the period only of said excessive pressure and hand operated means for moving the valve from one valve seat to the other, said valve operating means comprising a hand operated member relatively movable with respect to the valve seats, a valve 30 spindle having a limited movable relation with respect to the hand operated means, a spring connected with said member and acting on the spindle, the spindle provided with an abutment for engaging the wall of said member for limiting its spring actuated movement.

WM. CLINTON BROWN.
